UNITED STATES PATENT OFFICE

154,740

DESIGN FOR AN ATTIC FAN

Robert H. Bishop, Champaign, Ill.

Application February 21, 1947, Serial No. 137,076

Term of patent 14 years

(Cl. D26—7)

To all whom it may concern:

Be it known that I, Robert H. Bishop, a citizen of the United States, residing at Champaign, in the county of Champaign and State of Illinois, have invented a new, original, and ornamental Design for an Attic Fan, of which the following is the specification, reference being had to the accompanying drawing, forming a part thereof.

Figure 4 is a top plan view thereof, the dotted line illustrations included in Figures 1 to 3 being omitted for convenience of illustration only.

The characteristic features of my design reside in the portions shown by means of full lines in the drawing.

I claim:

The ornamental design for an attic fan, as shown and described.

ROBERT H. BISHOP.
